CLAIM

The ornamental design for a dispenser for a stethoscope personal protective equipment, as shown and described.

DESCRIPTION

FIG. 1 illustrates a perspective view of an embodiment of the dispenser for stethoscope personal protective equipment. FIG. 2 illustrates a front view of the dispenser for stethoscope personal protective equipment.

FIG. 3 illustrates a left side view of the dispenser for stethoscope personal protective equipment. The right side view is a mirror image.

FIG. 4 illustrates a rear view of the dispenser for stethoscope personal protective equipment.

FIG. 5 illustrates a top view of the dispenser for stethoscope personal protective equipment; and,

FIG. 6 illustrates a bottom view of the dispenser for stethoscope personal protective equipment.

The broken lines are used to illustrate environmental subject matter that form no part of the claimed invention.

1 Claim, 5 Drawing Sheets
